UNITED STATES PATENT OFFICE.

HENRY E. HENRICKS, OF BEAVER, PENNSYLVANIA, ASSIGNOR TO THE UNITED STATES SANITARY MANUFACTURING COMPANY, OF PITTSBURGH, PENNSYLVANIA, A CORPORATION OF PENNSYLVANIA.

PATTERN FOR BATHTUBS.

Application filed September 30, 1925. Serial No. 59,530.

This invention relates to bath tubs, and is particularly directed toward pattern for what is known as a single shield type of tub.

One object of my invention is to provide a pattern for a bath tub such that a shield is provided on the finished bath tub that is co-planar with a tub wall.

Another object of my invention is to provide a pattern for bath tubs such that a shield 10 is formed co-planar with a tub wall in a green sand mold.

A further object of my invention is to provide a pattern for a bath tub having attaching shields on at least one wall in which the 15 shield portions of the pattern are separable from and movable independently of the main body of the pattern.

In the single shield type one tub wall of a built-in tub is exposed to view and connection 20 with the building wall is made by a shield portion integral with the tub. Heretofore these shield portions have been so placed as to project from an end wall of the tub, thus exposing not only a side wall but also the tub 25 corner, and provide an irregular and rather unsightly contour. Shields of the above type have been molded integral with the tub by providing shield portions which might be withdrawn into the tub pattern proper before stripping the cope portion of the flask 30 from the pattern. It will be understood of course that in a commercial manufacture of bath tubs the molding is done by means of matched patterns, the cope and the drag being made up separately and brought together 35 on a casting floor. Generally speaking, all bath tubs are cast upside down so that the outside contour of the tub is formed in the cope portion of the mold.

Another form of shield which has been used is formed by extending the tub wall to the floor by means of a dry sand core which is put in place after the cope has been rammed and the pattern withdrawn. This style of 40 shield is also rather unsightly because in order to get metal of sufficiently uniform thickness to prevent cracking of the castings and also to eliminate defective castings by reason of loose sand, it has been necessary to set the shield back a short distance from the plane of the exposed tub wall so that there is a very definite "break" between the tub wall and the shield proper.

By the use of my pattern I provide a bath tub having a substantially plane shield extending the length of the tub, a portion of such shield forming one wall of the tub proper. Stated in another way, the side wall is extended beyond the body of the tub proper so as to provide a shield, this extension being 55 substantially co-planar with the tub wall.

The invention may be embodied in a tub of the recess type, that is, a tub extending from one wall to another and completely filling the space between, or to a corner tub which fits in one corner of the room and has one shield 60 on a side of the tub and another on the end thereof.

A pattern for making the above described bath tub, comprises a tub wall molding portion and a separate shield molding portion, the shield molding portion being adapted for movement relative to the tub pattern to a point substantially outside the mold. This shield molding portion is moved at a suitable 70 inclination to provide draft and permit a clean withdrawal of the shield molding portion from the mold after which the entire mold may be stripped from the main body 75 of the pattern without injury. It is possible 80 with this pattern to form the entire mold in green sand and to do away entirely with cores.

The flask is of course stripped from the pattern in a vertical direction and in a commercial foundry is handled by overhead cranes. Stripping pins are provided for lifting the flask a distance of about four 85 inches so as to insure a clean removal of the flask from the pattern before it is picked up 90 by the crane. These pins move the flask vertically and for a shield which terminates in a vertical line there is no draft whatever in the pattern. It is therefore necessary to impart to the shield molding portion of the pattern a component of movement toward the tub body so as to provide clearance and effect a clean removal of the shield molding portion 95 from the sand.

The tub walls usually slope toward one 100 another at the bottom of the tub and this means that the shield will be a plane which is inclined to the vertical. Since the cope and the drag are formed separately it is not necessary to provide draft on the tub walls 105 proper but draft is provided on the shield

portion or portions. Since the exposed face of the shield is co-planar with the outer face of the tub wall the draft is provided on the rear of the shield. In order to cause the shield molding portion to part cleanly from the faces of the cavity in the sand it is necessary to withdraw the shield molding portion at an angle to the vertical depending on the inclination of the tub wall. This angular motion is in addition to the endwise motion above described for providing clearance with respect to the end of the cavity in which the shield is to be cast.

The entire pattern is preferably tilted slightly during the molding operation so that the shield assumes a more nearly vertical position in the mold during ramming up than it does when the drag is matched with its corresponding cope. Supposing, for example, that a tub wall is designed to present an angle of 7° to the vertical, it is desirable to tilt the entire pattern about 1° 30'. It has been found in actual practice that this tilting of the tub body materially simplifies the molding operation and makes more certain the production of sharp clean corners on the casting.

In order to secure the above described movements of the shield molding portion I provide fluid operated cylinders under the control of the molder and suitably connected to the shield molding portions for withdrawing them from the flask at the desired time. Fluid operated cylinders provide a smooth and "soft" action which is exceedingly desirable in an operation of this character. Preferably the stripping pins above mentioned are also operated by a fluid cylinder. In the control system for the cylinders means is provided for actuating the several cylinders in sequence so that it is impossible to strip the flask from the pattern before the shield molding portions have been withdrawn.

In the accompanying drawings which illustrate a preferred embodiment of the invention:

Figure 1 is a side elevation of a bath tub made according to my invention;

Figure 2 is a horizontal section through the tub on the line II—II of Figure 1;

Figure 3 is an end view of the tub;

Figure 4 is a top plan view partly broken away, of a pattern for molding the tub shown in Figures 1 to 3 and showing one of the shield molding portions in place;

Figure 5 is a side view of the pattern shown in Figure 4 but with both the shield molding portions removed;

Figure 6 is a vertical section through a molding machine embodying the pattern shown in Figures 4 and 5;

Figure 7 is a vertical section on the line VII—VII of Figure 6, but showing a portion of the pattern broken away;

Figure 8 is a top plan view partly broken away, of the molding machine shown in Figures 6 and 7;

In the illustrated embodiment of the invention there is shown a tub body of the recess type comprising end walls 2 and a side wall 3. This wall is connected to the end walls 2 by curved corner portions 4. The side wall 3 has shield portions 5 extending beyond the corner portions 4 and end walls 2 so as to provide a substantially plane surface which, when the tub is in place, will conceal the outer surfaces of the end walls 2 and corner portions 4 as shown in Figure 1. The entire wall extends downwardly to the bottom of the feet 6 on the tub as shown in Figure 3. The usual roll rim 7 extends beyond the wall or shield as is common in tubs of this character.

In accordance with usual commercial practice, the tub is cast upside down and the cope and the drag are molded apart from one another by matched patterns as is well known in this art. It will be noted that the shield portions 5 are cast entirely in the cope as is the shield portion which extends below the tub bottom, which portion is indicated in the drawings by the reference character 8. It is necessary to provide draft for these shield portions and this is provided on the back face of the shield as shown at 9 in Figure 3. It will be further noted that the wall 3 is at an angle to a vertical line v—v. As heretofore described, the shield portion is cast by providing a corresponding portion on the pattern which is removed from the cope prior to stripping the same from the pattern proper to a point outside the pattern. It will be clear from Figure 3 that it is necessary to withdraw this loose piece at an angle to the vertical.

It will also be appreciated that the end wall 5a of the shield portions 5, being necessarily vertical by reason of the design of the tub, does not permit the allowance of draft on this portion of the pattern and therefore the shield molding portion must be moved inwardly toward the body of the tub in a direction lengthwise of the tub in the example shown. Of course if a corner type tub were being molded, it would be necessary to withdraw the end shield crosswise of the tub as well as inwardly in the other plane.

The pattern for forming the cope half of the mold is shown in Figures 4 and 5. It will be noted that it comprises a body portion indicated generally by the reference character B and movable shield portions one of which is shown in Figure 4 and indicated generally by the reference character S. The body portion is hollow and accommodates certain of the operating mechanism hereinafter described. The corners of the pattern body are cut away as shown in the drawings and parallel, sloping machined guide portions 10 are

provided for the shield portion S. The shield portion is fitted in place and a plate 11 is fitted thereto to hold it properly in the guides. As shown in Figure 5, these guides are sloped so that the shield portions are withdrawn at an angle from the vertical edge 5^a in a direction parallel to the major axis of the cope and permit a clean withdrawal.

Referring now to Figure 6 it will be seen that the shield portions S are mounted on slideable posts 12 provided with guides 13 near the bottom and also provided with operating racks 14. The racks 14 are engaged by pinions 15 mounted on a pair of cross shafts 16 which are journaled in the frame of the molding machine.

Keyed to the shafts 16 are pinions 17 which are engaged by racks 18 secured to a slide 19. The slide 19 is mounted in guides 20 secured to the frame of the molding machine and carries a pair of fluid actuated cylinders 21. The cylinders are double acting and are provided with pistons secured to piston rods 22 which are in turn fastened to the frame of the machine as indicated at 23. When actuating fluid, preferably air, is admitted to these cylinders the slide 19 is caused to move and the shield portions S are moved to the upper position indicated in Figure 6 or are moved downwardly to a point substantially outside the mold so as to permit withdrawal of the molded cope from the pattern. Adjusting screws 24 are placed in the head of each of the cylinders 21 and these are used to regulate the upper and lower positions of the shield portions S.

As above stated, it is desirable to tilt the entire pattern slightly and this is clearly shown in Figure 7 of the drawings. It will also be noted from that view that the posts 12 are so mounted that they move at an angle to the vertical as viewed in Figure 7 so as to secure a clean withdrawal from the sand not only of the front face 5^b of the shield portion, but also of the rear face 5^c thereof.

After the flask has been rammed up and the shield portions S withdrawn, the flask is ready for stripping from the main body of the pattern. This stripping is accomplished by pins 25 which are mounted for vertical movement in the frame of the molding machine. The pins are provided with rack teeth 26 engaging pinions 27 mounted on cross shafts 28. These cross shafts carry pinions 29 at their central portions and the pinions 29 are engaged by racks 30 mounted on a slide 31. The slide 31 carries a fluid cylinder 32. The cylinder is double acting and its piston rod 33 is secured to a cross piece 34. It will be seen that admission of fluid to one end or the other of the cylinder 32 will cause the slide 31 to move to the right or the left and cause the pins 25 to move up or down. It will be noted that the cylinder 32 and the associated mechanism are all within the body

portion of the pattern. This is not only a convenient disposition of these parts, but the cross piece 34 also serves as a brace for the front wall of the tub pattern, which wall is left unsupported at its ends by reason of the cutting out of the corner to provide for the shield portions S.

The upward movement of the pins 25 is limited by the design of the piston and cylinder while the downward movement thereof is limited by means of adjusting screws 35.

As heretofore stated, it is desirable to make sure that the cylinder 32 does not operate to strip the mold from the pattern until the cylinders 21 have been actuated to withdraw the shield forming pieces S from the flask. To this end the control mechanism for actuating the cylinders is provided with means for controlling the operation of the cylinders in a definite sequence. The cylinders are shown in Figures 7 and 8 as being in the position they will occupy when a mold has been rammed up before the shield forming portions have been withdrawn. When air is admitted to the left hand end of the cylinders 21 as viewed in the drawings, the cylinders and the slides to which they are attached move to the left, thus rotating the shafts 16 counterclockwise and causing the withdrawal of the shield portions S.

Attached to one of the cylinders 21 is an arm 41 for cooperation with a control system which comprises a rod 42 having a pair of operating fingers 43^a and 43^b thereon after the movement of the cylinders 21.

Continuing with the operation of the machine, the cylinders 21 move to the left until air is admitted to the right hand end of the cylinder 32 as viewed in the drawings. This causes the cylinder and the slide on which it is mounted to move to the right, thus rotating the shafts 28 in a clockwise direction and raising the stripping pins 25. These stripping pins engage the walls of the flask and lift it vertically from the pattern for a distance of about four inches. The flask is held in this raised position until it is picked up by the crane and taken away.

The completed cope half of the mold being now withdrawn from the machine, it is necessary to return the parts to their original position for molding the next tub. This is done by admitting air to the right hand ends of the cylinders 21 and causing them to move to the right. This movement is effective for rotating the shafts 16 in a clockwise direction and raising the shield portions S to the position shown in Figure 6 of the drawings. Air is admitted to the left hand end of the cylinder 32, thus causing the cylinder to move to the left and lower the stripping pins 25. The cooperating fluid system is designed so that it is impossible to put a flask in position for molding until the stripping pins have been

lowered and this means that no sand will be put inside the flask until the shield forming portions are in their upper position. This is of decided advantage since with an apparatus of this character wherein the shield portions are withdrawn from the confines of the flask during a molding operation there is necessarily left at some stage an opening through the pattern to the operating mechanism below. When the shield forming portions are in upper position, they close off this opening entirely and prevent any sand from falling into the machine proper. With the sequential operation of the cylinders as above described, there is never any danger of a workman getting sand into the operating parts of the molding machine.

If desired, one or both of each pair of shafts 16 and 28 may be extended to accommodate a hand lever for manual operation of the parts.

I have described a preferred embodiment of my invention as applied to a tub of the recess type. In a tub of this type the exposed wall is a side wall and the shield is an extension thereof. It will be understood that in a tub of the corner type an end wall becomes an exposed wall and one shield is an extension of this end wall. Where the terms "side wall" and "end wall" are used herein, they are meant to include an end wall which is exposed to view as will be apparent. In either case the exposed wall is inclined so that the junction of the unexposed wall with the exposed wall is a non-vertical line, while the shield extends beyond the same and terminates in a vertical line which is joined in the wall of the room. It will be further understood that while I have shown but one embodiment of the invention, it is not thus limited since it may be otherwise embodied within the scope of the following claims.

I claim:

1. A pattern for a bath tub having a shield portion which is an extension of a tub wall, including a tub body portion and a shield portion, co-planar with a wall of the body portion, the shield portion being relatively movable with respect to the body portion to a position substantially outside the mold portion formed by the pattern.

2. A pattern for a bath tub having a shield portion which is an extension of a tub wall, including a tub body portion and a shield portion, the shield portion being relatively movable with respect to the body portion to a position substantially outside the mold portion formed by the pattern, the direction of movement of such portion being in part inwardly of the pattern.

3. A pattern for a bath tub having a shield portion which is an extension of a tub wall, including a tub body portion and a shield portion, the shield portion being relatively movable with respect to the body portion, and

means for imparting to the shield portion a component of movement inwardly from its operative position so as to provide suitable pattern draft.

4. A pattern for a bath tub having a shield portion which is an extension of a tub wall, including a tub body portion and a shield portion, the outer face of the shield portion in a closed position being substantially flush with the outer face of a tub wall on the tub body portion.

5. A pattern for a bath tub having a shield portion which is an extension of a tub wall, including a tub body portion and a shield portion, the outer face of the shield portion in a closed position being substantially flush with the outer face of a tub wall on the tub body portion, and guides in the tub body portion for such shield portion.

6. A pattern for a bath tub having a shield portion which is an extension of a tub wall, including a tub body portion and a shield portion, the outer face of the shield portion in a closed position being substantially flush with the outer face of a tub wall on the tub body portion, the shield portion being relatively movable with respect to the body portion, and means formed on the engaging faces of the body and shield portion for causing the face of the shield portion which is flush with the tub wall to retreat therefrom on movement of the shield portion relative to the tub body portion.

7. A pattern for a bath tub having a shield including a tub body portion and a shield portion, the shield portion being relatively movable with respect to the body to a position substantially outside the mold portion formed from the pattern, and means for producing pattern draft on the shield portion.

8. A pattern for a bath tub having a tub wall inclined to the direction of stripping of the mold and a shield portion similarly inclined, including a tub wall molding portion and a relatively movable shield molding portion, the shield molding portion being adapted for movement to a point substantially outside the mold, such movement being along a line inclined to the direction of stripping.

9. A pattern for a bath tub having a tub wall inclined to the direction of stripping of the mold and a shield portion similarly inclined, including a tub wall molding portion and a relatively movable shield molding portion, the shield molding portion being adapted for movement to a point substantially outside the mold, such movement being along a line inclined to the direction of stripping, and also inclined to the inclination of the side wall to provide draft for the shield molding portion.

10. A pattern for a bath tub having a tub wall and an extension thereof forming a shield with an exposed face substantially co-

planar with the exposed face of the tub wall, including a shield molding portion having a back face which is inclined relative to the exposed face to provide pattern draft for the shield molding portion, and means for withdrawing the shield molding portion from the flask in a plane intermediate the front and rear faces thereof.

11. A pattern for a bath tub having a tub wall inclined to the direction of stripping of the mold and a shield portion similarly inclined, including a tub wall molding portion and a separate shield molding portion, the shield molding portion being adapted for movement relative to the tub pattern to a point substantially outside the mold, such movement being along a line inclined to the direction of stripping and also slightly inclined to the inclination of said side wall to provide draft for the front face of the shield molding portion, the shield molding portion having a rear face which is inclined to the front face of a greater amount than the inclination of the line of movement of the shield molding portion to the front face, whereby draft for the rear face of the shield molding portion is also provided.

12. A pattern for a bath tub having a non-vertical tub wall and a substantially coplanar shield portion, including a tub body portion which is inclined to reduce the angle which said tub wall would normally make with the direction of stripping, and a separate shield molding portion, the shield molding portion being adapted for movement to a point substantially outside the mold.

13. A pattern for a bath tub having a tub wall inclined to the direction of stripping of the mold and a shield portion similarly inclined, said shield portion further having a vertical end wall, including a tub wall molding portion, and a separate shield molding portion, the shield molding portion being adapted for movement relative to the tub pattern to a point substantially outside the mold, such movement being along the line slightly inclined to the inclination of the side wall to provide draft for the shield molding portion, and also being inclined toward the tub wall proper to provide draft for the vertical end wall.

14. A pattern for a bath tub having a body portion for defining a tub wall, a relatively movable shield portion constituting substantially an extension of the tub wall when in its molding position, and means for moving the

shield portion inwardly of the body portion and substantially in the plane of the wall, said moving means comprising a laterally and longitudinally movable support for the shield.

15. A pattern for a bath tub having a shield portion which is an extension of a tub wall, including a tub body portion and a tapered shield portion, the outer face of the shield portion in a closed position being substantially flush with the outer face of the tub wall on the tub body portion, guides in the tub body portion for such shield portion, and a support for the shield portion having longitudinal and lateral movement for moving the shield portion in said guides.

16. A pattern for a bath tub having a shield portion which is an extension of a tub wall, including a tub body portion and a shield portion, the outer face of the shield portion in a closed position being substantially flush with the outer face of a tub wall on the tub body portion, guides in the tub body portion for such shield portion, and means for moving the shield portion in said guides.

17. A pattern for a bath tub having a shield portion which is an extension of a tub wall, including a tub body portion and a tapered shield portion, the upper portion of the shield being of a smaller dimension than the lower portion, the outer face of the shield portion in a closed position being substantially flush with the outer face of a tub wall on the tub body portion, guides in the tub body portion for such shield portion, and means for moving the shield portion in said guides, whereby the upward movement of the shield portion in said guides moves the shield portion outwardly in the plane of the tub wall.

18. A pattern for a bath tub having a shield portion which is an extension of a tub wall, including a tub body portion and a tapered shield portion, the upper portion of the shield being of a smaller dimension than the lower portion, the outer face of the shield portion in a closed position being substantially flush with the outer face of a tub wall on the tub body portion, guides in the tub body portion for such shield portion, and means for moving the shield portion in said guides, whereby the downward movement of the shield portion in said guides moves the shield portion inwardly in the plane of the tub wall.

In testimony whereof I have hereunto set my hand.

HENRY E. HENRICKS.
